DESIGN FOR A TEXTILE FABRIC

Andre C. Bruine, Rutherford, N. J., assignor to Roth Fabrics Corp., New York, N. Y., a corporation of New York

Application December 5, 1935, Serial No. 59,916

Term of patent 3½ years

To all whom it may concern:

Be it known that I, Andre C. Bruine, a citizen of the United States of America, residing at Rutherford, in the county of Bergen, State of New Jersey, have invented a new, original, and ornamental Design for a Textile Fabric, of which the following is a specification, reference being had to the accompanying drawing, forming part thereof.

The figure of the drawing is a plan view of a piece of textile fabric embodying my design, the middle tones between black and white on said drawing representing different color values. The unit of the design within the dot and dash lines is repeated in the relation indicated, beyond the unit boundary lines.

I claim:

The ornamental design for a textile fabric substantially as shown and described.

In witness whereof, I have hereunto signed my name.

ANDRE C. BRUINE.
